Fig. 3.

UNITED STATES PATENT OFFICE

GEORGE W. MILLER, OF SAPULPA, OKLAHOMA

BIT ATTACHMENT FOR BAILERS

Application filed July 8, 1929. Serial No. 376,780.

My invention relates to drill bits and more particularly to a device of that character for use in connection with a bailer for well cleaning purposes; the principal object of the invention being to operate the bit with a bailer supported from the usual sand line, thereby eliminating the separate cable line ordinarily employed in operating a well cleaning bit.

In accomplishing this and other objects of the invention, I have provided improved details of structure, the preferred forms of which are illustrated in the accompanying drawings, wherein:

Fig. 1 is a vertical section of the lower portion of an oil well, illustrating operation of the bit in connection with a bailer.

Fig. 2 is an enlarged detail perspective view of the bit.

Fig. 3 is a central vertical section through the bit on the line 3—3, Fig. 1, showing its connection with a bailer.

Fig. 4 is a transverse section on the line 4—4, Fig. 3.

Referring in detail to the drawings:

1 designates an oil well extending through cap rock 2 and terminating in a shot hole 3 in the oil sand 4, and 5 designates sand, rock or débris collected in the shot hole incident to shooting of the well, reaming or natural dislodgement from the walls of the shot hole.

The well hole is lined with casing 6 supported on the cap rack, and adapted for receiving and guiding a bailer 7 for lowering into the well by a sand line 8; the bailer key 33 here shown fitted with a drill bit 9 constructed in accordance with my invention.

The drill bit 9 includes an elongated body 10 having rounded edges 11 and 12, and provided with the usual water courses or grooves 13 extending downwardly from a head portion 14 and terminating on opposite sides of a flared cutting tip 15.

Provided on the head portion 14 is a coupling shank 16 adapted to fit snugly within the lower end of the bailer and to be substituted for the ordinary bailer bottom, and having spaced stop bosses 17 for engagement in bayonet slots 18 in the walls of the bailer, and which may be secured in the slots by the usual bailer latch 19 and set screw 20.

Extending centrally through the shank 16 is an opening 21 connecting through an axial channel in the head with branch ports 22 communicating with the grooves 13 and adapted for conducting fluid through the head 55 of the bit into the bailer. The opening 21 is provided with a reduced lower end forming a tapering seat 23 in the shank at the upper end of the body for cooperating with a ball check valve 24 retained in the opening 60 by retainer pins 25, and adapted for preventing return flow of fluid through the opening.

When the bit is to be employed in connection with the bailer, the ordinary bailer bottom is removed to permit insertion of the coupling shank 16 into the bailer and engagement of the stop bosses 17 in the bayonet slots 18.

With the bit secured to the bailer, and the bailer attached to the sand line, the connected members are lowered to the bottom of the well 70 for a cleaning operation.

The drill bit is reciprocated at the bottom of the well by the sand line for breaking up the rock or encrusted sand in the shot hole 75 into small particles, for delivery into the bailer with the fluid through the ports 22 and valved opening 21.

When the bailer is filled with the sediment laden fluid the members may be withdrawn 80 from the well to permit emptying of the bailer, and the operation repeated until all débris is removed from the shot hole.

It will be obvious that the bit may be readily attached to or removed from a bailer to 85 suit the conditions of different wells, and without altering the coupling means of the conventional type bailer, thereby effecting a considerable saving of time in the cleaning of wells.

What I claim and desire to secure by Letters Patent is:

1. In combination with a bailer having a bayonet slot, a bit having a head provided with an axial channel and branch ports leading downwardly from said channel, a reduced shank on said head receivable in the bailer, and having an axial opening of greater diameter than said axial opening in the head to form a valve seat, a lug on said 100

shank receivable in the bayonet slot of the bailer, a valve movable vertically in said shank to engage said seat, and means on the shank restricting upward movement of the valve.

- 5 2. A drill bit for attachment to a bailer, including a body portion having longitudinal grooves, ports opening to said grooves, and an axial channel communicating with said ports, a shank on the upper end of the body reduced to engage in the lower end of the bailer and having an axial bore of greater diameter than said channel to form a valve seat at the upper end of the body channel, a ball valve movable in the shank bore, a stop member mounted in the shank to limit upward movement of the valve, and a lug projecting laterally outwardly from the shank for latching the bit to the bailer.
- 10 15 20 In testimony whereof I affix my signature.
GEORGE W. MILLER.
